UNITED STATES PATENT OFFICE.

GEORGE W. CONSTANTINE, OF CHICAGO, ILLINOIS.

HOG-SCRAPING MACHINE.

SPECIFICATION forming part of Letters Patent No. 645,418, dated March 13, 1900.

Application filed December 11, 1899. Serial No. 739,988. (No model.)

To all whom it may concern:

Be it known that I, GEORGE W. CONSTANTINE, a citizen of the United States, residing at Chicago, in the county of Cook and State 5 of Illinois, have invented new and useful Improvements in Hog-Scraping Machines, of which the following is a specification.

My invention relates to improvements in hog-scraping machines, and particularly to 10 what is known in this art as the "hooking-on hook"—namely, the hook which is connected with the jaw-hook which the operator attaches to the lower jaw of the hog after the hog has been thrown out of the scalding-tub and onto 15 the usual slotted or channeled table preparatory to being carried to the scraping-machine proper.

Heretofore, as far as I know, the hooking-on hook (after the jaw-hook was inserted into 20 the hog) was placed upon the table with the front or point in the slot thereof in the path of the cross-bars of the usual chain or carrier and said hook was held in position by hand until a cross-bar of the chain caught 25 the hook and carried it and the attached hog to and through the scraper. Thus under the prior methods the "hooker-on," as the operator is called, held the hook in his hand until a cross-bar of the chain or carrier was about to 30 pass him, when he hooked the point of the hook onto the cross-bar and repeated the operation with the next hog. The present invention comprehends facilitating the rapid handling of the hogs by devising a hooking-on hook which may be placed upon the table 35 and retained in such a position that it may be automatically caught by the cross-bar of the chain and carried to the scraping-machine, thus enabling the operator to handle 40 the hogs with more despatch, as all he has to do is to attach the hook to the hog and lay the hook on the table with its point projecting through the slot and then repeat the operation with the next hog coming from the 45 scalding tub or vat, the hook end of the preceding hook remaining properly placed to be automatically caught by the cross-bar of the chain and transported without requiring the personal assistance or attention of the operator after the initial operation of placing the 50 hook on the table is performed.

The invention therefore consists, essen-

tially, in the combination, with a slotted table and a chain or carrier mounted beneath the same, of a hooking-on hook provided with 55 means for retaining it in operative position on the table, whereby it may be automatically engaged by the carrier.

It also consists of the parts and the constructions and combinations of parts, which 60 I shall hereinafter describe, and point out in the claims.

Referring to the accompanying drawings, forming part of this specification, and in which like letters of reference indicate corresponding parts, Figure 1 is a plan view of my improved hooking-on hook in position on the slotted table, the said table being shown in dotted lines. Fig. 2 is a longitudinal sectional view on the line xx of Fig. 1 and showing in 70 dotted lines a portion of the chain or carrier. Fig. 3 is a plan view in dotted lines of a portion of the chain or carrier and showing a cross-bar in full lines. Fig. 4 is an enlarged perspective view of one of my improved hooks 75 detached.

The table A is of the usual or any desired pattern and size and construction. It is placed proximate to the scalding tub or vat, and upon it the hogs are thrown by a mechanism used in connection with the tub or vat. These features and mechanisms, as well as the scraping mechanisms which are usually placed near the end of the table opposite to the scalding tub or vat, are well-known in the 85 art and constitute no essential portion of my invention.

Suitably journaled below the table A is a chain or endless carrier B of any well-known or desired type and having cross-bars a at 90 intervals about eight (8) feet apart, said cross-bars each having by preference a groove b near its center to facilitate the engagement therewith of the hooking-on hook. This hook C is of substantially the type shown in Figs. 95 2 and 4—namely, it has a comparatively straight body portion with a hook c at one end to engage one of the cross-bars a of the chain or carrier, and it has an eye d at the opposite end to engage a link e , which connects the usual jaw-hook e' with the hooking-on hook.

The essence of my invention and the real point of improvement is in forming or pro-

viding the hooking-on hook with a transverse or laterally-extending projection, which prevents the hook dropping through the slot of the table when said hook is placed therein 5 and retains the hook in position so that its point or hook end may be automatically caught by a cross-bar of the chain or carrier when it reaches said hook. In the specific form of hook shown and to which I do not limit myself, as various modifications of it may be used with success and without departing from the spirit of my invention, the said hooking-on hook is formed or provided with a lug or ear *g*, rising from its upper side at a point 10 just back of the front end of the hook, said lug or ear having a cross-pin *h* projecting transversely from each side and sufficiently beyond the plane of the walls of the slot in the table to prevent the hook dropping through 15 the slot when placed therein.

In operation with my improved hooking-on hook the operator or hooker-on inserts the usual jaw-hook into the under jaw of the hog already on the table, as aforesaid, and then 20 places the hook into the slot in the table. The lugs or pins *h* prevent the hook dropping through the slot and support said hook with its front or hook end in the path of the cross-bars of the chain or carrier beneath the table. 25 It remains in this position and without further attention on the part of the operator until a cross-bar passes the point, when said bar automatically engages the hook and transports it and the attached hog to the scraping mechanism. Under the old methods the operator 30 not only placed the hook in position in the slot, but he was compelled to hold onto the hook until the arrival of a cross-bar, when he would hook the point or front of the hook 35 into its engagement with the cross-bar. Such an operation was dangerous, because of the possibility of the operator having his hand caught between the hook and the table, and it consumed enough time to represent in the 40 aggregate a large loss to the operator or his 45

employer. In fact, actual experiment has shown that by the use of my improved hook the operator can in a given length of time handle about one-third more hogs than when using the old forms of hooking-on hooks. 50

The improvement is simple and effective and is of such a character that it may be applied to already-existing hooks with but little expense and without any change or modifications of the existing machinery. 55

Having thus described my invention, what I claim as new, and desire to secure by Letters Patent, is—

1. In a hog-scraping machine, the combination with a slotted table and a chain or carrier mounted beneath the same, of a "hooking-on hook" adapted to be placed within the slot of the table and provided with a vertically-extending lug or ear having lateral supports for maintaining said hook in position 60 with its front or hooked end in the path of the chain or carrier whereby it is automatically engaged thereby. 65

2. In a hog-scraping machine, the combination with a slotted table and a chain or carrier mounted beneath the same, of a "hooking-on hook" to be placed in the slot of the table and having a hook-shaped front end and an opposite end adapted to engage a jaw-hook, said "hooking-on hook" having a vertically-extending lug or ear provided with a lateral projection or support extending beyond the plane of the side walls of the slot and adapted to prevent the hook dropping through said slot and to hold it operatively 70 in position for automatic engagement with the chain or carrier. 75

In testimony whereof I have hereunto set my hand in presence of two subscribing witnesses.

GEORGE W. CONSTANTINE.
